WARNING AND SIGNALLING LIGHT OR SIMILAR ARTICLE

Arthur C. Heehler, Park Ridge, and Albert E. Ganzert,
Chicago, Ill., assignors to The Pyle-National Company,
Chicago, Ill., a corporation of New Jersey

Application June 2, 1955, Serial No. 36,333

Term of patent 14 years

(Cl. D72—1)

Fig. 1

Fig.2

Fig.3

Figure 1 is a perspective view of a warning and signalling light or similar article embodying our new design;

Figure 2 is a top plan view of the structure shown in Figure 1; and

Figure 3 is a side elevational view of the structure shown in Figure 1.

We claim:

The ornamental design for a warning and signalling light or similar article, as shown.
